UNITED STATES PATENT OFFICE

HARRY VARWIG AND FRANK CALDWELL, OF CINCINNATI, OHIO.

SHOE-HEEL FASTENER.

1,297,423.

Specification of Letters Patent. Patented Mar. 13, 1919

Application filed April 30, 1918. Serial No. 231,782.

To all whom it may concern:

Be it known that we, HARRY VARWIG and FRANK CALDWELL, citizens of the United States, and residents of Cincinnati, in the county of Hamilton and State of Ohio, have invented certain new and useful Improvements in Shoe-Heel Fasteners, of which the following is a specification.

Our invention is an improvement in shoe heel fasteners, and has for its object to provide a device of the character specified, especially adapted for connecting wooden heels to ladies' shoes, wherein means is provided adapted to be arranged between the heel and the sole to connect the heel to the sole without the use of nails in connection with the sole.

In the drawings:

Figure 1 is a vertical section through one embodiment of the invention;

Fig. 2 is a perspective view of the fastener shown in Fig. 1;

Fig. 3 is a view similar to Fig. 1, showing another embodiment of the invention;

Fig. 4 is a top plan view of the sole;

Fig. 5 is a perspective view of the fastener shown in Fig. 3;

Figs. 6 and 7 are perspective views of other embodiments of the invention;

Fig. 8 is a perspective view showing a modified form of lug.

In the embodiment of the invention shown in Figs. 1 and 2, the heel 1 is connected to the sole 2 by means of an angle plate, the said plate consisting of a portion 4 which has an opening 5 and a portion 6 which has its end rounded, as shown. The portion 4 of the fastener is held in an opening in the heel 1, with about half the length of the portion 6 extending beyond the upper face of the heel, the said face being shaped to fit the sole, as shown.

A screw 7 is passed through the opening 5 into engagement with the heel, and the sole has a slot or opening for permitting the passage of the portion 6 of the plate. After the portion 6 has been passed through this opening in the sole, the portion extending beyond the sole is bent down upon the sole as indicated at 8, thus clenching the plate to the sole. It will be noticed that the sole is countersunk to receive this portion 8 so that there is no hump or obstruction at this point.

The construction just described is designed to assist in holding the heel to the

sole as an auxiliary to the holding nails or the like. It will be noticed that the plate 4-6 are placed near the rear of the heel or sole, upon which point there is the greater strain.

In the embodiment of the invention shown in Figs. 3 to 5, inclusive, the fastener comprises a plate 9 having the shape of the upper end of the wooden heel 10, the said plate being adapted to fit upon this face of the heel and to cover the same as indicated in Fig. 3. The plate does not extend to the edge of the heel at any point, as shown in Fig. 4, and the plate is provided with openings for receiving screws 11 for connecting the plate to the heel.

On the upper face of the plate is a series of upstanding lugs 12, three lugs being provided in the present instance, and these lugs are adapted to extend through slots or openings in the sole 13 and to be bent down or clenched upon the sole, which is countersunk to receive them in the same manner as for the portion 6 of the plate shown in Fig. 2.

In Fig. 6, instead of a plate, a horseshoe-shaped bar 14 is used, the said bar having openings for the screws 15 for engaging the heel and having lugs 16 on its upper face for engaging the sole.

In Fig. 7 the plate 17 is X- or cross shaped having four arms, each of which has an opening for receiving a screw 18 for engaging the heel, and the lugs 19 which correspond to the lugs 12 and 16 of Figs. 5 and 6 are struck up from the material of the plate.

The use of the devices shown in Figs. 6 and 7 is precisely the same as that shown in Fig. 5, the lugs 16 and 19 being clenched to the sole, while the plate is held to the heel by the screw. With the construction of Figs. 5, 6 and 7 no nailing is necessary between the sole and the heel, the fasteners serving to fasten the heel to the sole.

In Fig. 8 is shown a modified construction of spur or lug. In this construction the plate 20, which may be any of the forms shown, has spurs or lugs which are bifurcated or forked, as indicated at 21, to pass through the sole 22. This is for the purpose of preventing the spreading of the cut, in thin leather, through which the lug passes.

We claim:

In combination with a shoe having a sole

and a heel, means for securing the heel to the sole, said means comprising a plate of approximately the size of the top of the heel and having means for securing the same to the heel, the plate having lugs, the sole having openings through which the lugs extend and the said lugs being adapted to be bent down upon the upper face of the sole, said lugs being near the edges of the plate to provide at widely separated points attachment for the heel.

HARRY VARWIG.
FRANK CALDWELL.
